UNITED STATES PATENT OFFICE.

TAYLOR BURROWS, OF LONDON, ENGLAND, ASSIGNOR TO THE FLAX COMBING SYNDICATE, LIMITED, OF SAME PLACE.

GILL-BOX MACHINE FOR PREPARING FIBERS.

SPECIFICATION forming part of Letters Patent No. 633,793, dated September 26, 1899.

Application filed December 29, 1897. Serial No. 664,401. (No model.)

To all whom it may concern:

Be it known that I, TAYLOR BURROWS, engineer, a subject of the Queen of Great Britain, residing at Staines, London, England, have invented certain new and useful Improvements in or Relating to Gill-Box Machines for Preparing Fibers, of which the following is a specification.

This invention relates to that class of machines known as "gill-boxes" for opening and preparing fibers preparatory to combing and is designed more especially for treating vegetable fibers, such as flax, hemp, china-grass, or the like.

15 The advantages obtained by the improved preparing-machine are principally in the softening action of lapping the material as it is drawn from the gills or teeth onto an endless sheet or belt which is made to run over and encircle one of the drawing-rollers, (a second and similar endless sheet or belt running over and encircling the other drawing-roll,) so that the flax or other fiber is between the top and bottom sheets or belts, and as it is 25 lapped around the top sheet consequently (by the continuous running between the drawing-rollers under pressure) is softened and opened and parallelized. The gills, which have a surface speed superior to that of the 30 feed-rollers or porcupine feed, clear away the greater part of the straw and impurities from the fiber fed on, and the straw, &c., falls under the machine. At the same time the fiber is opened and lashed by the pins or teeth of the 35 gills and so prepared for being drawn out into a sliver ready for the combing-machine, which latter will separate the long spinable fibers from the short or noil. For clean long-scuted flax, which requires only opening 40 up and drawing into lap or sliver, one or two pairs of ordinary feed-rollers are good; but where tow in its tangled form is to be treated a porcupine roller working in a dish (which may be preceded or followed by a pair of 45 feed-rollers) is advantageous.

In order that this invention may be easily understood, I will proceed to fully describe same with reference to the drawings hereunto annexed.

50 Figure 1 is an end elevation—*i. e.*, looking in the direction of the arrow 1, Fig. 2—of a

gill-box machine having the present improvements applied thereto and constructed and arranged to act according to the present invention. Fig. 2 is a longitudinal vertical section on the line 2 2, Fig. 1. Fig. 3 is a local detail view showing the modified arrangement for feeding the fiber to the gills.

A is the frame or support.

B' are ordinary feeding-rollers which are 60 mechanically revolved in the usual or any suitable manner, and B^x is the ordinary feeding-apron, passing around one of the rollers B'.

C C are the gills, the same being ordinary screw-gills of the well-known character and arranged and acting as is well understood, and therefore it is not necessary to further illustrate same or more fully describe same here. If desired, these screw-gills may be made to advance at an increasing speed by means of 70 variable screws, which impart the advancing motion to said gills.

D is a dabbing-brush extending across the full width of the gills, said brush being carried on the arm D', fixed to a shaft D², journaled in bearings carried on the frame A. D³ D⁴ are cranks or arms extending from the opposite ends of said shaft D², to which they are rigidly fixed, or only one arm D³ or D⁴ may be used. E E are eccentrics or cams (slowly 80 revolved by connection with some working part of the machine) whereby said arms D³ D⁴ are caused to oscillate said shaft D² through part of a revolution, and consequently the brush D is raised and lowered into the teeth 85 or pins of the gills, and thus dabs the fiber into same and insures the fibrous material being pressed right into said teeth or pins at a position close up to the feeding-rollers.

F G are the drawing-rollers, revolved from 90 the main driving-shaft (not shown) of the machine in the usual or any suitable manner.

H is the upper endless sheet or belt passing around the upper drawing-roller F and the idle adjustable roller F'.

I is the lower endless sheet or belt passing around the lower drawing-roller G and the idle adjustable roller G'. The roller F' is journaled in sliding blocks J, which latter are adapted to slide in or on the supports J' and are adjustable thereon by means of the set-screws J², while the roller G' is similarly ar-

ranged--viz., is journaled in the slide-blocks K, adapted to slide on the support K' and adjusted by means of the set-screws K² and thus the endless sheets or belts (which may 5 advantageously be of leather) can be respectively stretched or adjusted as desired. Each of the supports J' is pivoted on a standard J³, attached to the frame A, and is provided with a curved extension J⁴, slotted at J⁵. A set- 10 screw J⁶ passes through this slotted extension into the frame H. By means of these parts the roller F' and belt H can be adjusted relatively to the belt I.

M is an idle presser-roller (carried by the 15 arm's M') resting against the belt H as the latter passes around the upper drawing-roller F, and thereby guiding the fibers downward in between the belts H and I.

N N are the ordinary set-screws for adjusting the pressure on the drawing-rollers F G.

The drawing-rollers F G may advantageously be fluted, and said rollers F G have a peripheral speed considerably greater than the speed of advance of the gills C, the advance 25 of the latter in turn being much quicker than the peripheral speed of the feed-rollers B B'.

The operation is as follows: The fibers are drawn out and opened and (after being acted 30 on by the gills C) are led between the endless sheets H I and are formed into a lap around the endless sheet H, on which the fibers are continuously wound up, and as this lapped fiber passes around and around it is repeatedly pressed between the drawing-rollers F G, 35 and is consequently softened and very beneficially acted upon. As the first fibers appear between the belts H and I the attendant lifts them onto the belt H. When the fiber reaches the other end of the belt H, it is guided down 40 and again passes between the belts. After the formation of the lap begins it goes on automatically. When a sufficient quantity of the fiber has accumulated on the belt H, it is separated by pulling on same by hand and removed and

on another machine is drawn out into a continuous sliver in readiness for the combing machine or may be otherwise removed or treated in any desired manner.

In the modification shown in Fig. 3 the porcupine roller X (in combination and acting 50 in conjunction with the dish Y) is introduced between the feed-rollers B B' and the gills C in order to first open and straighten the fibers before they are acted on by the gills C and at the same time to allow the longer fibers to slip 55 unbroken through the porcupine teeth of said roller X.

Many changes in the details of the machine may be made without departing from the spirit of my invention, and I wish it to be expressly understood that I do not limit myself to the exact details shown and described.

Having thus described my invention, what I claim as new, and desire to secure by Letters Patent of the United States, is—

1. In a gill box or machine for opening and drawing fibers, the combination of feeding devices, traveling gills, drawing-rollers, loose rollers, belts passing over said drawing-rollers and said loose rollers, and a freely-swinging 70 pressure-roller placed near the inner end of the upper belt, substantially as described.

2. In a gill box or machine for opening and drawing fibers, the combination of feeding devices, a porcupine roller and dish, traveling gills, a brush above said gills, means for oscillating said brush, fluted drawing-rollers, loose rollers, belts passing around said drawing-rollers and said loose rollers, means for adjusting said loose rollers to tighten or loosen 75 said belts, means for adjusting the upper belt toward or away from the other belt and a freely-swinging pressure-roller, near one end of the upper belt substantially as described.

TAYLOR BURROWS.
